(57) **CLAIM**

I claim the ornamental design for a brake disk, as shown and described.

DESCRIPTION

FIG. 1 is a perspective view of a brake disk showing my new design;

FIG. 2 is a front elevational view thereof, the rear being a mirror image;

FIG. 3 is a left side view thereof;

FIG. 4 is a right side view thereof;

FIG. 5 is a top plan view thereof; and,

FIG. 6 is a bottom plan view of the brake disk.

The broken lines in the drawings illustrate portions of the brake disk which form no part of the claimed design.
